UNITED STATES PATENT OFFICE.

OLIN A. WATSON, OF CHICAGO, ILLINOIS.

MOUTH-PIECE FOR WIND-INSTRUMENTS.

SPECIFICATION forming part of Letters Patent No. 325,715, dated September 8, 1885.

Application filed March 25, 1884. (No model.)

To all whom it may concern:

Be it known that I, OLIN A. WATSON, of Chicago, county of Cook, and State of Illinois, have invented certain new and useful Improvements in Mouth-Pieces for Musical Wind-Instruments, of which the following is a full, clear, and exact description, that will enable others to make and use the same, reference being had to the accompanying drawings, forming a part of this specification.

The object of this invention is to provide a mouth-piece for wind-instruments which is adapted to be adjusted so as to increase or diminish the depth of the cup by means of the pressure and relaxation of pressure from the lips of the player, as will be hereinafter more fully set forth and claimed.

Figure 1 is an elevation of a mouth-piece embodying my improved features; Fig. 2, a vertical central section in the plane 2 2, Fig. 1; and Fig. 3 a side elevation of the tubular shank and cup.

Referring to the drawings, A represents an open cap-piece; B, a ferrule, and C a tubular shank.

The tubular shank C is provided with the enlarged end D, the interior of which is cupped out, forming the contracted cup a, as shown in Fig. 2. The exterior surface of the cup 30 end D is provided with an annular groove for the reception of the packing-ring a', placed between the same and the interior surface of the cap A for the purpose of forming an air-tight joint. The open cap A, having the rim 35 a", is provided with the exterior thread, a", adapting the same to engage with the correspondingly-threaded interior surface, a', of the ferrule B, whereby these parts may be lengthened or shortened by turning the cap in or 40 out, as may be required. The ferrule B is provided with the inwardly-projecting flange b, engaging with the under side of the enlarged end D, by which arrangement these parts are retained in proper relation and permit of a

free longitudinal movement on the shank C 45 independent of the screw-threaded adjustment of the cap and ferrule. The shank C is provided along a portion of its exterior surface with the screw-thread b', which receives the hand-nut d, adapted to have a threaded connection with said shank. The spiral spring E encircles the shank C between the nut d and the ferrule B, the ends of the spring bearing on these parts, respectively. The tension of the spring is regulated by means of the hand-nut so as to suit different players. This construction and arrangement permit of the cap and ferrule being first adjusted so as to give the cup the required depth necessary to produce the lower notes, while a pressure from 50 the lips of the player will force the cap and ferrule down on the shank, thus diminishing the depth of the cup and enabling the player to produce the higher notes, the spring serving to return the parts to a normal position when 55 the pressure on the cap is relaxed.

It will be readily seen and understood with what convenience and facility the player is enabled to increase or diminish the depth of the cup without having to remove the lips 7c from the mouth-piece, which is not the case where the adjustment is accomplished by a screw-threaded connection alone.

Having thus described my invention, what I claim as new, and desire to secure by Letters 75 Patent, is—

In a mouth-piece as described, the combination, with the cap-piece A, of the ferrule B, provided with the inwardly-projecting flange b, the tubular shank C, provided with the enlarged end D, the spiral spring E, and the tension-nut d, all constructed and arranged to operate as set forth.

OLIN A. WATSON.
